UNITED STATES PATENT OFFICE

CHARLES H. OSLUND, OF WORCESTER, MASSACHUSETTS, ASSIGNOR TO THE LIQUID CARBONIC CORPORATION, OF CHICAGO, ILLINOIS, A CORPORATION OF DELAWARE

WIPING DEVICE FOR LABELS

Application filed December 5, 1929. Serial No. 411,889.

This invention relates to the smoothing down of comparatively inflexible labels which are used on many articles including baking powder cans, ketchup bottles and the like.

The principal objects of the invention are to provide a practical and simple means to secure the sticking of the labels which are covered with glue or are made of thick materials so that they are not very flexible and have a tendency to stick up from the article at the edge after they have been wiped down in the ordinary way by brushes, rollers and the like; to provide means whereby, when the wiping operation is performed, the wiper will be drawn back automatically so that the further passage of the article along in the machine will not result in the passage of the wiping device backwardly over the label, thus avoiding any tendency on the part of the machine to undo the work of the wiper; to provide a construction for this purpose suitable for a labeler in which the articles travel along a path; to provide means for causing the wiper to move with the article as it passes along and for allowing a certain flexibility of action to permit it to move around the article through an arc to securely wipe down the label and to provide it in a duplicate form to enable the machine to wipe down both the leading and the following edges of the label.

Other objects and advantages of the invention will appear hereinafter.

Reference is to be had to the accompanying drawings in which

Fig. 1 is a plan of a part of a rotary labeling machine with a preferred embodiment of this invention applied thereto;

Fig. 2 is an elevation of an upright shaft of this machine showing the means thereon for actuating the labeling device;

Fig. 3 is a plan of one of the elements of this machine showing the means by which a

plurality of wipers are associated together for performing the desired work;

Fig. 4 is a plan of one of the individual wipers on enlarged scale, showing the flexibility of motion;

Fig. 5 is a plan of the rotary table showing diagrammatically two positions of the article to be labeled and the two wipers performing their operations, the upper one just ready to be applied to the leading edge of the label;

Fig. 6 is a similar view showing the completion of the wiping of the leading edge of the label and the complete withdrawal of the wiper after the following edge has been pressed down;

Fig. 7 is a similar view showing the position as the leading edge of the label has been fully wiped down and the labeling device is being withdrawn from it;

Fig. 8 is a plan showing another form of this invention as applied to an endless belt or chain carrier labelling machine moving in a straight line;

Fig. 9 is a view of one of these labeling devices showing the final pressing down of the leading edge of the label and beginning of the act of pressing down the other edge of the label, and

Fig. 10 is a similar view showing the latter wiping device as having completed the pressing down of the following end of the label.

The invention is shown in the first seven figures as being applied to a labelling machine of the type shown in a previous patent granted to myself and John E. Johnson, August 17, 1926, Patent No. 1,596,372.

In these figures I have shown the invention as applied to an ordinary rotary table labeling machine comprising a table or carrier 10 which rotates continuously with a vertical shaft 11. This table has stations at which the cans B, bottles or other articles to be labelled are clamped down by clamps. I have shown a label grip 15 which grips the

label centrally on the front of the can and holds it while the can is passing around a part of the circumference. These parts are all old and the invention is not necessarily limited to this type of machine but is particularly adapted thereto.

On the shaft 11, which is driven in any desired way, I provide a gear which through gearing and shaft, shown in said patent, 10 drives a vertical shaft 21 which extends up above the table and is located beyond the circumference. This shaft by bevel gears drives a horizontal shaft 22 and a vertical shaft 23 over the table. On each of the shafts 15 21 and 23 is fixed a collar 25 having an arm 26 projecting out from it. Below the collar is a loose hub 27 provided with an arm 28 secured to the hub by a screw 29 or the like. A light spring 31 extends from the arm 26 20 to the arm 28. It will be seen that the collar 25 will rotate with the shaft 23 and that through the spring the rotation of the shaft 23 will carry along the hub 27 behind it. The hub is yieldingly connected with the shaft so 25 that if it meets an obstruction it will be retarded.

From this hub extend radial arms 34 shown here as three in number. These are mounted so that they can be adjusted radially. On each arm there is a vertical stud 36 having a pivoted wiper or scoop 37 on it which is yieldingly held in place by a spring 35. In the present instance these wipers are concave in shape and lined with soft material 30 as felt or rubber. They are mounted to freely swing on the studs 36, being held back by the springs so as to be all in the same horizontal plane.

On the shaft 23 is fixed by a screw 40 a collar 41 having an arm 42 carrying a vertical shaft 43. On the shaft 43 is an arm 44 carrying a vertical cam roller 45. On the bearing of the shaft 23 is a cam 46, mainly circular, but having as many projections as there 45 are arms 34. On the shaft 43 is a sleeve 47 fixed to it and carrying an arm 48 which has an adjustable screw 49.

The screw 49 is adapted to engage one arm 34 at times and push it and, of course, 50 all three arms back when the roll 45 is pushed out by the cam 46.

On the other shaft 21 there are the same devices and the wipers preferably are located in a similar manner about this shaft and 55 spaced equally apart. Three of them are shown, although the number is dependent upon the speed of the table and the spacing of the bottles thereon, among other things.

With the parts arranged in the manner 60 shown in these drawings, each of the shafts 21 and 23 makes a third of a turn while the table turns far enough for the can or bottles to move from any position to the next one. The shafts 21 and 23 rotate in the direction 65 of the outer arrows in Figs. 5, 6 and 7 and

the table is also rotating in the direction of the arrow at its circumference. A can marked B in Fig. 5 comes around into a position to engage a wiper 37 on the shaft 21, as shown in that figure. At the same time another can B', preferably the next one, which has been through the process, is just receiving its last pressure from the next wiper on the shaft 23. By the time the table has rotated from the position shown in Fig. 5 to the position shown in Fig. 6, the wiper has been left behind by the can B', and has come out of contact with it. At the same time the rotation of the shaft 21 causes the wiper to be pressed against the label L held to the can B at the center of the front thereof by the gripper 15. On account of the yielding action and the particular directions of the paths of the table and wipers, the result of this is that this wiper presses against the label with a yielding pressure throughout a wide area and all the way along this path. By the time the table gets to the position shown in Fig. 6, this wiper is pressing against the rear end of the label with considerable pressure owing to the fact that the wiper has the same radius as the can and is held in that position thereby, the spring yielding for that purpose.

But as the table moves along from this position to the position shown in Fig. 7, the can moving faster than the driven speed of the wiper, the tension on the spring is released and the spring tends to cause the wiper to keep up with the can and apply pressure to it considerably. As the can B moves from the position shown in Fig. 6 to that shown in Fig. 7 the tendency of the spring 35 would be to force the rear edge of the wiper against the label. As the table and shaft turn with adjacent sides moving in the same direction, this would tend to wipe the label backwardly and perhaps detach it at its end. In order to bring the wiper out away from the label, the cam 46 at this time acts on the roller 45 and turns the shaft 43 so as to move the screw 49 against one of the arms 34. This results in swinging the structure comprising the three arms 34 and the hub 27 on the shaft 21 backwardly. This moves the wiper out away from the can and label entirely. This avoids any possibility of the wiper again engaging the label and pushing it back at its end after it is wiped down.

It will be noticed that the wiper, instead of having a single point contact with the label as in the prior patent above mentioned, has contact at all times over a wide area of it and holds the label positively in the curved position in which it is to remain on the can. Furthermore by the rolling of a roller over the paper on the can there is a tendency to form a wave in the label ahead of the roll and this of course is entirely obviated by the present construction. On the inside, so to speak, the wiper, which previously has not

been mentioned, now comes around in the direction of the arrow and on account of the converging curved paths of this wiper and the can, it engages the label and acts on it the same way on the following end of the label.

The principles of this invention can be carried out in other forms and in Figs. 8, 9, and 10 is shown the application of this invention to a labeling machine involving a traveling conveyer 50 of the endless apron type. Here the cans B pass along with this conveyer in a straight line and the operation is practically the same as has been described above. The label L is held in position by the label grip 15 as before and a wiper 37 on one side is mounted on an arm 51 pivoted to an arm 52 on a shaft 53. This arm 52 has another arm which makes a lever of it and is held yieldingly in position toward the conveyor by a spring 54 up against a stop 55. There is also a stop pin 56 for the arm 51 and a spring 57 for moving that arm back against the stop whenever it is possible.

Starting in the position shown in Fig. 8 the wiper or scoop 37 is shown just having come into contact with the label by reason of the forward motion of the can on the conveyer. Now as it moves from that position to the position shown in Fig. 9, the wiper moves round the can circumferentially, as in the other case, until it comes to the end of the label, the spring 57 yielding to allow that to occur. As the can passes on, in this case, the can moves away from the wiper and there is no tendency for the wiper to move backwardly toward the can, the spring 57 moving it in a rearward direction with respect to the motion of the can. The other wiper 37 on the other side is shown in inactive position in Fig. 8 and just coming into contact with the label in Fig. 9 and finally in Fig. 10 in the same relative position as the other wiper which is shown in Fig. 9, that is, the can just about to leave the wiper.

It will be seen that in this case the functions are practically the same as in the other, although the mechanism is different, to provide for the straight line motion of the conveyer.

This is an important improvement because it has not been practicable heretofore to label certain articles, as for example, baking powder cans by machine. As far as I know they are all labeled by hand at the present time. The labels are extra heavy and are soaked in paste, so that they are wet on both sides and machines cannot handle them. I now apply these heavy labels by this machine, in a dry state on the front side, as easily as thin flexible labels are applied by the best machines heretofore on the market.

Although I have illustrated and described only two forms of the invention I am aware of the fact that other modifications can be made therein by any person skilled in the art

without departing from the scope of the invention as expressed in the claims.

Therefore, I do not wish to be limited in this respect but what I do claim is:—

1. In a labeling machine, the combination with movable means for supporting the articles to be labeled, of a concave label wiping device, means for applying said label wiping device to the surface of the label on the article, and means for moving said label wiping device forwardly with the article to be labeled throughout a part of the travel of said article to hold the edge of the label in contact with said article throughout a wide area for a substantial period of time. 70

2. In a labeling machine, the combination with a movable support for the articles to be labeled, of a curved label wiping device having a substantial area adapted to engage the label, and of the same curvature as the article to be labeled, and means for holding said wiping device in contact with the label on the article and moving it with the article but at a different rate so that the wiping device will contact with a wide area of the label and yet move along the label until it reaches the edge thereof. 85

3. In a labeling machine, the combination with movable means for supporting the articles to be labeled, of a concave label wiping device, means for applying said label wiping device to the surface of the label on the article to hold the label down throughout a wide area, and a movable support on which said wiping device is pivotally mounted, whereby the wiping device can be held in contact with the label for a period of time and yet will be free to change its angular position relative to the article as the article moves along to keep the wiper in contact with the label until it reaches its edge. 100

4. The combination with a label wiper comprising a concave member having a soft interior lining, the inner surface of which fits the surface of the article to be labelled, of means for moving said wiper circumferentially and slidingly along the surface of the article to be labelled while the entire concave surface is in contact with the article. 110

5. In a labeling machine, the combination with a movable support for the articles to be labeled, of a curved label wiper having a concave surface fitting the article to be labeled, a movable arm on which the wiper is mounted pivotally and yielding means for holding the wiper in a certain position, whereby when the wiper engages the article it will be free to yield so as to move around the article through the arc of a circle on the circumference of the article. 125

6. In a labeling machine, the combination with a rotary table for the articles to be labeled, of a concave label wiper fitting the articles to be labeled, a rotary arm, said wiper being pivotally mounted on said arm, and a 130

spring connecting the wiper with said arm on the side toward which the articles are adapted to approach the wiper, whereby when the article and wiper come into contact the spring will yield to allow the wiper to swing against the article and move circumferentially along its surface.

7. In a labeling machine, the combination of a rotary shaft, arms projecting from said shaft, a label wiper pivotally mounted on each arm, and means for swinging the arm backwardly when the wiping operation has been completed to prevent the wiper from moving forwardly further and undoing the wiping operation.

8. In a labeling machine, the combination with means for moving the articles to be labeled, of a rotary shaft, arms projecting from said shaft, a label wiper pivotally mounted on each arm, yielding means for moving the wiper in a certain direction for engagement with an article to be labeled, the arm and the article to be labeled moving forward in the same general direction, whereby the wiper will move circumferentially along the surface of the article and means for swinging the arm backwardly when the wiping operation has been completed to prevent the wiper from moving forwardly further and undoing the wiping operation.

9. In a labeling machine, the combination with a movable support for the articles to be labeled, of a curved label wiper having a substantial area adapted to engage the label, and of the same curvature as the article to be labeled, means for moving the wiping device in a curved path, said wiper being pivotally and yieldingly mounted, a stationary cam, and means cooperating with the means for moving the wiper adapted to engage said cam and swing the wiper back at the end of the wiping operation to remove it out of contact with the article to be labeled.

10. In a labeling machine, the combination of a movable support for the articles to be labeled, a rotary shaft, an arm movable with the shaft, a wiper pivoted on said arm, a stationary cam, a cam roll pivoted on said shaft for engaging the cam and means movable with said cam roll for moving the arm backwardly at the end of the wiping operation to remove the wiper bodily from the article to be labeled.

11. In a labeling machine, the combination with an endless apron carrier for the articles to be labeled, of a lever pivoted at the side thereof, an arm pivoted on said lever, a concave wiper carried by said arm and yieldingly connected with the lever, said wiper being located in the path of the article to be labeled, whereby as the article comes along the wiper will engage it and move it

along its surface as the article proceeds along its path.

12. The combination with a label wiper comprising a concave member having a soft interior lining, the inner surface of which fits the surface of the article to be labelled, of means for moving said wiper circumferentially on the surface of the article to be labeled, about the axis of said article as a center.

In testimony whereof I have hereunto affixed my signature.

CHARLES H. OSLUND.
